(57) **CLAIM**

The ornamental design for a dosing closure, as shown and described.

DESCRIPTION

FIG. 1 is a perspective view of the of the dosing closure according to the invention, showing the front and left side of the dosing closure.

FIG. 2 is a perspective view of the of the dosing closure showing the back and right side of the dosing closure.

FIG. 3 is a left side elevation view of the dosing closure.

FIG. 4 is a back elevation view of the dosing closure.

FIG. 5 is a front elevation view of the dosing closure.

FIG. 6 is a right side elevation view of the dosing closure.

FIG. 7 is a top plan view of the dosing closure; and,

FIG. 8 is a bottom plan view of the dosing closure.
